UNITED STATES PATENT OFFICE.

ROXANNA A. NORTON, OF NEW YORK, N. Y.

DESIGN FOR A DISPENSING CABINET OR SIMILAR ARTICLE.

Application filed January 15, 1925. Serial No. 12,062. Term of patent 14 years.

To all whom it may concern:

Be it known that I, ROXANNA A. NORTON, a citizen of the United States, and a resident of the city of New York, borough of Manhattan, in the county and State of New York, have invented a new, original, and ornamental Design for Dispensing Cabinet or Similar Article, of which the following is a specification, reference being had to the accompanying drawing, forming part thereof.

The figure is a perspective view of a dispensing cabinet or similar article, showing my new design.

I claim:

The ornamental design for a dispensing cabinet or similar article, as shown.

ROXANNA A. NORTON.
